UNITED STATES PATENT OFFICE

135,220

DESIGN FOR A CONTAINER FOR COLOGNE BOTTLE OR SIMILAR ARTICLE

John D. Buckingham, Chicago, Ill., assignor to Lucien Lelong, Inc., Chicago, Ill., a corporation of Illinois

Application December 4, 1940, Serial No. 97,061

Term of patent 14 years

To all whom it may concern:

Be it known that I, John D. Buckingham, a citizen of the United States and a resident of the city of Chicago, in the county of Cook and State of Illinois, have invented a new, original, and ornamental Design for a Container for Cologne Bottle or Similar Article, of which the following is a specification, reference being had to the accompanying drawing, forming a part thereof.

On the drawing:

Figure 1 is a top plan view of the container for cologne bottle or similar article, showing my new design

I claim:

The ornamental design for a container for cologne bottle or similar article, as shown.

JOHN D. BUCKINGHAM.
